UNITED STATES PATENT OFFICE.

WILLIAM J. SIMON, OF BROOKLYN, NEW YORK, ASSIGNOR TO L. D. BLOCH & COMPANY,
OF NEW YORK, N. Y., A CORPORATION OF NEW YORK.

DESIGN FOR A HANDLE FOR A SMOKING TABLE.

Application filed June 7, 1928. Serial No. 27,030. Term of patent 3½ years.

To all whom it may concern:

Be it known that I, WILLIAM J. SIMON, a citizen of the United States residing at Brooklyn, county of Kings, and State of New York, have invented a new, original, and ornamental Design for a Handle for a Smoking Table, of which the following is a specification, reference being had to the accompanying drawing, forming part thereof.

The figure is a front elevation of a handle for a smoking table, showing my new design.

I claim:

The ornamental design for a handle for a smoking table, substantially as shown.

In testimony whereof I hereto affix my signature.

WILLIAM J. SIMON.
